UNITED STATES PATENT OFFICE.

OTTO R. GRASS, OF CHICAGO, ILLINOIS, ASSIGNOR TO ORO-TONE COMPANY, OF CHICAGO, ILLINOIS, A CORPORATION OF ILLINOIS.

DISK FOR SOUND BOXES.

Application filed March 27, 1926. Serial No. 97,833.

My invention relates to diaphragms for sound boxes for talking machines and method of making same and has for its primary object the provision of a diaphragm having an 5 annular extending area of flexure therein formed by reducing the thickness of the diaphragm by machining the diaphragm around its margin and thereafter forming as an addition thereto, an annular stiffening rib 10 on said diaphragm adjacent the cut-away portion, and also offsetting a portion of the cut-away portion thus providing a diaphragm having a circular extending area of flexure adjacent the edge of the diaphragm 15 where it is secured to the sound box, thus producing a diaphragm which is bodily movable from a point near the outer edge thereof, thus reproducing the sounds in a very much clearer and better manner than what has been 20 possible to accomplish heretofore, and also doing away with the blasting sound so common in the reproductions of music, speech or sound from a phonograph record.

A further object of my invention is the 25 provision of a diaphragm in which the outer edge of the diaphragm is reduced to a minimum thickness by machining so that the area of flexure of the diaphragm is uniform throughout its entire portion thereby resulting 30 in a substantial equal body movement of the free portion of the diaphragm in the sound box.

As is well known in the phonograph art, in order to obtain tones which are clear and in 35 which the reproduction thereof is as near the natural tone of the voice or instrument from which the tone was originally recorded, it is necessary to have the entire body portion of the diaphragm vibrate so that the 40 movement of vibration of the diaphragm is as great at the outer portion of the diaphragm as it is in the middle of the diaphragm or at the point to which the stylus bar is attached or substantially so. If a diaphragm of equal 45 thickness is produced throughout its entire area and secured in the sound box around its outer marginal edges of ordinary construction, the greatest movement of the diaphragm will be at the point where the stylus bar is 50 secured to the diaphragm, usually at the central point thereof, and the amount of movement of the diaphragm or flexure thereof will decrease from the central point out to the marginal edge. In my improved structure I 55 seek to reduce the central vibratory move-

ment of the diaphragm to a minimum and secure a body movement of the unattached or free portions of the diaphragm by producing a diaphragm having the outer edges machined to a minimum degree of thinness consistent with strength and produce in the central portion of the diaphragm a pair of concentric rings which serve to stiffen the central portion of the diaphragm and produce a 60 diaphragm having an area of flexure around the outer edge adjacent the machined part of the diaphragm. 65

Another and further object of my invention is the provision of a diaphragm which is simple in construction and which is easy to 70 manufacture and also in which the area of the flexing portion of the diaphragm is positioned adjacent the outer ring or fastening point of the diaphragm.

Another and further object of my invention is the provision of a method of making diaphragms for sound boxes and in which the diaphragm blank is machined on its outer marginal edge and then is pressed into the proper contour to give a stiff body portion 80 and have the area of flexure as near the outer marginal edge of the diaphragm as possible after it is mounted in the sound box. 75

These and other objects of my invention will be more fully and better understood by 85 reference to the accompanying sheet of drawings and in which:

Figure 1 is an elevational view of a blank used in making diaphragms for sound boxes;

Figure 2 is a cross sectional view of the 90 blank shown in Figure 1;

Figure 3 is an elevational view after the blank shown in Figure 2 has been machined off around its outer marginal edge;

Figure 4 is a cross sectional view of the 95 blank shown in Figure 3;

Figure 5 is an elevational view of the diaphragm after it has been pressed between a pair of molds and ready for insertion in the sound box;

Figure 6 is a cross sectional view of the diaphragm shown in Figure 5; and

Figure 7 is a view partially in section and partially in elevation of a sound box showing my improved diaphragm mounted 105 therein.

Referring now specifically to the drawings and in which like reference characters refer to like parts throughout, a disk 10 is shown which is a composition of various materials 110

such as rubber, celluloid and the like, and which are produced in commercial quantities, the said disk 10 being cut to any size desired and of uniform thickness throughout its entire area, the said blank being approximately thirty thousandths of an inch in thickness throughout its entire area. In following my improved method, the blank 10 is machined in any suitable manner (Figures 3 and 4) by cutting away a portion of the blank 10 around the outer marginal edge thereof and inward to a point somewhat further than necessary to provide an edge sufficient for the mounting of the diaphragm, thus producing a shoulder portion 11 which extends around the disk 10 and the outer portion 12, the said portion 12 being machined down to approximately five thousandths of an inch in thickness.

After the operation just above described has been performed, the blank 10 is preferably placed between a pair of dies and the said dies are heated slightly and the diaphragm subjected to pressure so that an annular recess 13 is produced upon one side of the said diaphragm blank and preferably with an inner annular recess or groove 14 being produced with a corresponding rib 15 being produced on the outer side of the diaphragm and with an annular rib or ridge 16 being produced opposite the recess 13, the said recess 13 being approximately double the width of the rib 16 and extending over so that approximately one-half the width of the machined part 12 of the outer edge of the diaphragm is pressed up out of alignment with the body portion of the diaphragm and producing a portion 13, the under side of which is in alignment with the under side of the rib 16. It will thus be noted that the part 12 of the machined portion is turned at 17 (as shown in Figure 6) in an upward direction so that when the diaphragm is mounted in a sound box the point of flexure of the diaphragm is between the shoulder 11 and the point 17 of the machined portion 12 of the diaphragm. A hole 18 is punched in the central portion of the diaphragm for the purpose of attaching the stylus bar to the diaphragm.

As illustrated in Figure 7, a sound box is shown and which comprises a base 19 having a collar 20 adapted to fit over the end of the usual tone arm and having a spring pressed ball 21 therein adapted to hold the sound box in engagement upon the tone arm. A threaded plug 22 is provided with a spring 23 which serves to hold the ball 21 in position. A cover plate 24 is provided which is secured to the portion 19 by means of screws 25, 25, the said cover plate having a stylus bar 26 pivotally mounted thereon in the usual manner, the stylus bar 26 having a recess 27 therein within which the upper end of a needle is adapted to sit with a screw 28 adapted

to hold the needle in position. The stylus bar is secured to the diaphragm 10 by means of a screw 29 which passes through the upper end of a stylus bar 26 and through the hole 18 in the central portion of the diaphragm 10. An annular member 30 is provided against which the portion 12 of the diaphragm 10 rests with a second annular member 31, these members ordinarily being rubber covered so that the outer marginal edge 12 of the diaphragm 10 is compressed tightly between the members 30 and 31 when the sound box is assembled, as shown in Figure 7.

It will be thus understood that the blanks, as shown, which are approximately thirty thousandths of an inch in thickness, have the outer marginal edges reduced in thickness by cutting away a portion of the disk to approximately five thousandths of an inch in thickness and thereupon the diaphragm is preferably placed in dies which are heated and the diaphragm molded into the condition shown in Figure 6 and thus the body portion of the diaphragm is strengthened by means of the annular ribs 15 and 16 so that a point of flexure is provided in the diaphragm beginning at the point 17 and ending adjacent the shoulder 11 (Figure 6) and the diaphragm being so materially reduced in thickness and so thin, receives the vibrations from the stylus bar 26 and thus the plane of movement at the outer edge of the diaphragm is substantially equal to the plane of movement of the diaphragm at the middle portion thereof where the stylus bar is joined to the diaphragm. It will be further understood that while I prefer to form the diaphragm with the rib adjacent the cut-away portion, that this operation may be dispensed with and merely by cutting away a portion of the diaphragm a uniform area of flexure is formed which has not heretofore been obtained in the manufacture of diaphragms.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. A diaphragm comprising a disk materially reduced in thickness on its outer periphery and having a circular channel formed in one side of said disk which partially includes the portion of said disk which is reduced in thickness, whereby an area of flexibility is formed in said diaphragm adjacent the outer periphery thereof.

2. A diaphragm comprising a disk having a portion thereof reduced around its marginal edge on one side only, and a plurality of concentric ribs formed therein on one side of said disk, and a plurality of channels concen-

- trically arranged on the opposite side of said disk, the outer channel extending underneath the outer rib and into said cut away portion, whereby an area of flexure is formed adjacent 5 the outer periphery of the said diaphragm.
3. A diaphragm comprising a disk having a portion thereof materially reduced in thickness extending circumferentially around said disk and having an annular groove on one 10 side thereof and a rib on the opposite side of said disk, said groove and rib being opposite each other, said rib being of lesser width than the said groove and spaced apart from the outer marginal edge of said disk whereby 15 an area of flexure is formed adjacent the outer periphery of the said disk.
4. A diaphragm comprising in combination
- a disk having its outer edge materially reduced in thickness on one side only and having an annular rib formed therein upon one 20 side of said disk and an annular depression formed on the opposite side of said disk of greater width than the said rib and having a portion thereof opposite the rib, said depression extending into the portion of said disk 25 which is reduced in thickness whereby an annular area of flexure is formed on said disk adjacent its outer edge, and having a portion of said disk extending beyond the said area of flexure to provide means for mounting the 30 said diaphragm in a sound box.

Signed at Chicago, Illinois, this 20th day
of March, 1926.

OTTO R. GRASS.
